UNITED STATES PATENT OFFICE.

WILLIAM T. SULLIVAN, OF CINCINNATI, OHIO.

BINDING POST FOR CALENDAR PADS AND THE LIKE.

Application filed March 1, 1927. Serial No. 171,890.

This invention relates to improvements in binding posts for calendar pads and pads of a like or similar nature.

An object of this invention is to provide a simple binding post for holding calendar pages, or other leaves or pieces of paper, against a base that will not wobble or sag when the leaves are torn from the binding post.

Another object of this invention is to provide a binding post for the purposes stated that is inexpensive to manufacture and requires a minimum of parts, which parts may be assembled in a minimum of time and with little effort.

These and other objects are attained by the means described herein and disclosed in the accompanying drawings, in which:

Fig. 1 is a perspective view of a calendar pad having embodied therein a binding post of this invention.

Fig. 2 is a sectional view taken on line 2—2 of Fig. 1.

Fig. 3 is an elevational view of the individual parts of the improved binding post of this invention.

The improved binding post 10 is mounted on and extends at right angles to a suitable base 11.

The base 11 has formed therein near its upper edge a perforation 12 for hanging or suspending the base from a suitable support. The base 11 is provided intermediate its edges with perforations 13 through which the binding post 10 extends.

The binding post 10 comprises a sleeve 14 having a radial flange 15 formed at one end and a longitudinal bore 16 extending through the sleeve. The bore 16 in the sleeve and the bore 13 in the base are in alignment and have extending through them a fastening means, commonly called a paper fastener 17. The paper fastener 17 comprises an enlarged head portion 18 from which a pair of arms 19 and 20 extend. The arms 19 and 20 pass through the bore 16 in the sleeve and the perforation 13 in the pad. The outer ends 21 of the arms 19 and 20 extend through and beyond a washer 22. It should be noted that the head 18 of the paper fastener 17 is larger than the outside diameter of the sleeve 14. It should also be noted that the washer 22 is larger than the perforation 13 formed in the base 11.

The operation of my device is as follows. A plurality of calendar pages 23, or other

leaves or pieces of paper, provided with perforations 24 are mounted about the sleeve 14. The radial flange 15 of the sleeve 14 is then placed upon the base 11 so that the bore 16 of the sleeve 14 is in axial alignment with the perforation 13 in the base 11. The paper fastener 17 is then inserted through the bore 16 and perforations 13 until the head 18 of the fastener 17 abuts the outer edge of the sleeve 14. The washer 22 is now placed on the arms 19 and 20 of the fastener 17 and against the base 11. The ends 21 of the arms are bent in opposite directions and at angles to said arms thereby securing the base 11 between the washer 22 and the peripheral flange 15.

It should be noted that the binding post 10 is secured to the base 11 and extends permanently at right angles to said base. Further the sheets comprising the calendar pad may be readily removed from the post without leaving any stubs on the post and without causing the post to sag or slump.

What is claimed is:

1. The combination of a base having a perforation therein, a sleeve having a bore in alignment with the perforation in the base, a flange carried by the sleeve and contacting the base, a paper fastener comprising a pair of bendable arms, and a head on the paper fastener abutting one end of the sleeve, the bendable arms extending through the bore in the sleeve and through the perforation in the base having their ends bent upon the base for securing the base between the flange on the sleeve and the bent portions of the arms and for securing the sleeve at substantially right angles to the plane of the base.

2. The combination with a base having a perforation therein, of a sleeve having a bore in axial alignment with the perforation in the sleeve, one end of the sleeve contacting the base, and means for securing the sleeve at substantially right angles to the plane of the base, the said securing means comprising a head for engaging one end of the sleeve and bendable arms extending from the head through the bore in the sleeve and through the perforation in the base, the ends of the arms being bent upon the base for securing the base between the said bent ends of the arms and the end of the sleeve.

3. The combination of a pad of individually tearable and detachable perforated sheets having aligned perforations, a base

- for the pad of sheets, a sleeve having a radial flange at one end, the flange being disposed between the pad and the base and abutting the base, the sleeve extending through the perforations in the sheets, and a fastening device comprising a head portion and a bendable arm portion the head portion extending beyond the sleeve and precluding movement of the sheets beyond the sleeve, and the bendable arm portion extending through the sleeve and the base and bent radially of the sleeve at the back of the base for clamping the sleeve on the base.
- 15 4. The combination of a pad of individually detachable perforated sheets having their perforations in alignment, a base for the pad of sheets, a sleeve having a radial flange at one end, the flange being disposed between the pad and the base and abutting the base, the sleeve extending through the perforations in the sheets, and a fastening device extending through the sleeve and the base and having its one end 20 extending radially beyond the sleeve for precluding movement of the sheets off of the

end of the sleeve, the other end of the fastening device being bent radially of the sleeve and lying along the rear face of the base for clamping the sleeve, and the base together.

10 5. The combination of a base having a perforation therein, a sleeve having a bore in axial alignment with the perforation of the base, one end of the sleeve contacting the base, a fastening means comprising a head and an arm extending from the head, the arm of the fastening means extending through the aligned bores in the sleeve and base, and a perforated washer carried by 30 the free end of the arm and contacting the base, the end of the arm being adapted to clamp the base between the washer on one side of the base and the end of the sleeve on the other side of the base and for securing the sleeve at substantially right angles to the plane of the base.

15 In testimony whereof, I have hereunto subscribed my name this 21st day of February, 1927.

WILLIAM T. SULLIVAN.
